UNITED STATES PATENT OFFICE.

WILHELM CARL BERLING, OF BUFFALO, NEW YORK.

TIMING DEVICE FOR IGNITION-MAGNETOS.

1,115,890.

Specification of Letters Patent.

Patented Nov. 3, 1914.

Application filed March 2, 1912. Serial No. 681,234.

To all whom it may concern:

Be it known that I, WILHELM CARL BERLING, a citizen of Sweden, subject of the King of Sweden, residing at Buffalo, in the county of Erie and State of New York, have invented a new and useful Timing Device for Ignition-Magnetos, of which the following is a specification, reference being had to the accompanying drawings, illustrating same.

This present invention is a modification of my invention set forth in my co-pending United States patent application Serial No. 652,926, filed Oct. 5, 1911, on timing device for ignition magnetos.

My invention relates to spark-timing devices for ignition magnetos, especially used in connection with internal combustion engines, and to mechanism for efficiently operating and controlling such spark-timing devices.

The principal objects of my invention are, to provide an improved spark-timing device for magneto generators or ignition magnetos, as will be hereinafter more fully set forth; to provide improved mechanism for operating and controlling the spark-timing devices of magneto generators or ignition magnetos, as will be hereinafter more fully set forth; to provide improved means for eliminating the usual intermittent jerk of the armature in such magnetos, caused by the intermittent uneven magnetic pull on the armature at certain parts of each revolution, and at the same time permitting an adjustable connection between the armature and the driving shaft or mechanism; to provide improved means for driving the armature of the magneto and at the same time permitting of angular adjustment of the armature relatively to the driving shaft while the magneto is running; to provide an improved ball-bearing connection for giving the armature of the magneto an angular adjustment relatively to the driving shaft while the magneto is running, thereby eliminating unnecessary friction in the device during such adjustment and also during the ordinary running of the magneto; to provide improved means for preventing the armature from working back to retarded position during the running of the magneto; and to provide other improvements in such apparatus as will be hereinafter more fully set forth.

Other objects will be apparent from the following specification.

In the accompanying drawings illustrating the preferred form of my invention, Figure 1 is a longitudinal cross-sectional view of the timing device of the invention, with portions shown in elevation, showing also an armature of a magneto in elevation, and the timing device connecting the armature with a driving shaft therefor; 60 Fig. 2 is a side elevation of the housing member for the timing device of Fig. 1, showing also a longitudinally-disposed key set therein; Fig. 3 is an end elevation of the ring which encircles the housing member 70 shown in Fig. 2, for causing the operation of the timing mechanism; Fig. 4 is a plan view of the lower half of the ring shown in Fig. 3, showing also one of the diagonally-set lugs thereon used for causing 75 the operation of the timing mechanism; Fig. 5 is a side elevation of the key carried by the housing member of Fig. 2; Fig. 6 is a side elevation of the sleeve member located inside of the housing of Fig. 2 and 80 operable longitudinally therein to control the timing mechanism; Fig. 7 is an end elevation of the crab-like friction clutch used to cause the armature of the magneto to revolve evenly with the driving shaft; Fig. 85 Fig. 8 is a perspective view of the friction clutch of Fig. 7 and a portion of the spirally-formed armature shaft to which the clutch is secured; Fig. 9 is a perspective view of a portion of the driving shaft, showing the 90 longitudinal slots therein and the cup-shaped portion in which the friction clutch of Figs. 7 and 8 engages; Fig. 10 is a perspective view of the collar member used for connecting the armature shaft with the driving shaft and for giving the armature shaft 95 an angular adjustment relatively to the driving shaft; Fig. 11 is a transverse cross-sectional view of the crab-like spring clutch 100 shown in Figs. 7 and 8 and used in the device of Fig. 1, by means of which the usual intermittent jerk on the armature of the magneto is eliminated, showing the interior construction of the clutch; and Fig. 12 is a simplified end elevation of a magneto 105 field and armature, showing the armature in the position corresponding to the maximum voltage of the magneto for a given speed, when the armature is running in the direction of arrow α .

Like characters refer to like parts in the several figures.

At this stage of the art it is well known that the interruption of the inductive circuit of a magneto must be advanced for high speeds of the engine, and retarded for low speeds of the engine, to get the best efficiency. One method commonly used for advancing and retarding such interruptions, 10 is to shift the interrupter on the frame of the magneto, but as this method causes the interruption to take place at various positions of the armature relatively to the field, and consequently at various points on the 15 voltage and current waves of the magneto, it is very objectionable, because in this case the magneto generally gives the spark on a low or inefficient part of the current wave. Thus when the engine is running at low 20 speed and the interruption is retarded, the spark is very weak, and sometimes insufficient, especially in starting the engine on the magneto.

In my present invention I entirely do 25 away with the objectionable features above mentioned, by always interrupting the inductive circuit at a point where the maximum spark is produced, that is, at the highest peak of the current wave or curve, 30 regardless of whether the interruption is advanced or retarded, and at all speeds of the engine. Thus with my arrangement the engine can be readily started on the magneto, at full retard, and run much more efficiently when started.

In my improved apparatus for accomplishing this result, one part of the interrupter is preferably secured rigidly to the frame of the magneto, and the other part 40 to the armature, in such positions as to always break the inductive circuit of the magneto at the point where the maximum spark is produced, regardless of all other conditions. For advancing and retarding 45 the interruptions, I provide a device adapted to shift the armature shaft angularly, that is, forwardly and backwardly, relatively to the engine shaft or driving shaft, either while the apparatus is running or 50 while it is stationary, but in particular for doing this efficiently while the apparatus is running. This device comprises a collar member operable longitudinally along the driving shaft and spirally along the armature shaft, a sleeve member operable purely 55 longitudinally within a housing for the apparatus and having a ball-bearing connection with the said collar member, and a ring operable purely transversely around the housing and having diagonally-set lugs 60 thereon operating in diagonally-formed slots in the said sleeve member to cause the longitudinal movement of the latter. In connection with this I also provide a friction 65 clutch acting between the armature shaft

and the driving shaft for eliminating the usual continual jerk or vibration on the apparatus, and for preventing the armature and the apparatus associated therewith from constantly working toward retarded position as is usually the case. 70

I will now describe my invention more in detail as follows: Referring to the drawings illustrating the preferred form of my invention, 1 is the driving shaft which is 75 connected with the engine, this shaft member having longitudinally-disposed slots 2 2 therein and a cup-shaped portion 3 formed thereon.

4 is the spirally-formed armature shaft, 80 which is preferably connected with the magneto armature 5 as shown. The shafts 1 and 4 preferably run in ball bearings as shown in Fig. 1.

6 is a collar member having longitudinally-disposed arms 7 7 thereon working in the slots 2 2 of the driving shaft member, and a spirally-formed hole 8 there-through by means of which the collar member 6 works spirally on the spirally-formed portion 4 of the armature shaft. From these parts it will be readily seen that if the collar member 6 be given a longitudinal movement it will shift the armature shaft 4 angularly relatively to the driving shaft 1, 95 thereby advancing or retarding the "spark" of the magneto relatively to the engine in a manner well understood. The means I preferably employ for moving the collar member 6 longitudinally to advance or retard the "spark", comprises a sleeve member 9 keyed within a housing 10 by a longitudinally-disposed key 11 carried by the housing 10, so that the sleeve member 9 has a purely longitudinal movement within the 105 housing 10, and a ring 12 encircling the housing 10 and working between annular flanges 13 13 thereon whereby the ring 12 is limited to a purely transverse movement on the housing 10, the ring 12 carrying diagonally-set lugs 14 14 working in diagonally-formed slots 15 15 in the sleeve member 9 to impart the longitudinal movement to the latter when the ring 12 is turned on the housing 10. The sleeve member 9 is connected with the collar member 6 by means 110 of a ball-bearing connection 16 whereby the members 9 and 6 are movable longitudinally together and whereby the collar member 6 is rotatable within the sleeve member 9 and 120 relatively thereto. Any suitable mechanism, such as a lever, may be attached to the arm 17 of the ring 12 for turning the latter on the housing 10.

The friction clutch I preferably employ 125 comprises a hub portion 18 fixedly secured to the armature shaft 4 so as to revolve therewith, and a pair of spring arms 19 19 adapted to spring out in the cup-shaped portion 3 of the driving shaft member 1, 130

against the inner surface of the cup-shaped portion 3, with sufficient force to cause the armature 5 to revolve evenly with the driving shaft 1, thus overcoming the uneven 5 magnetic jerk on the armature and yet permitting the armature to adjust itself angularly relatively to the driving shaft when the spark-timing mechanism is operated, by the arms 19 19 slipping in the cup-shaped portion 3. This clutch provides against the usual intermittent jerk on the spark-timing apparatus where any sort of an adjustable 10 connection is provided between the armature shaft and the driving shaft, and also provides against the creeping of the armature to retarded position where such apparatus is used, both of which are due to the intermittent uneven magnetic pull on the armature during each revolution of its 15 operation. The spring arms 19 19 normally stand outside of the circle 30 but are adapted to be sprung inwardly to conform to the circle 30. The clutch preferably has a curved spring member 31 extending throughout 20 the lengths of the arms 19 19 and the connecting portion 32 and secured between metal parts preferably as shown in Fig. 11, the arms 19 19 being slightly separated from the portion 32 at 33 33 to permit the 25 spring 31 to have the proper action on the arms 19 19. When the apparatus is assembled as shown in Fig. 1, the arms 19 19 of the clutch are squeezed together to conform to the circle 30 and then the clutch as 30 a whole is slipped into the cup-shaped cylindrical portion 3 on the shaft member 1, the arms 19 19 when released springing out against the inner surface of the portion 3 so as to act as a friction clutch on same. 35 The arms 19 19 of the clutch spring out against the portion 3 with enough force to overcome the usual intermittent jerk on the armature hereinbefore mentioned, and thereby cause the armature to run smoothly 40 with the engine, thus eliminating the objectionable vibration on the apparatus. This grip between the clutch 26 and the portion 3 is also forcible enough to keep the armature from gradually working to 45 retarded position as hereinbefore mentioned, but it is not strong enough to prevent the clutch 26 from slipping in the portion 3 when the lever 17 is operated to advance or retard the spark, which slipping takes place 50 during such operation. The back magnetic pull on the armature tending to work it and the timing device and levers connected therewith to retarded position, is thus prevented from doing so by the action of the clutch 26. The clutch also helps to drive 55 the armature 5 from the driving shaft 1, and in so doing prevents excessive wear on the three-fingered collar portion 6. These features of the device of this invention, 60 provided by the clutch 26, greatly increase 65

the efficiency and serviceability of such devices and apparatus.

As the arm 17 works up and down in a plane at right-angles to the armature shaft, the device is well adapted to be connected 70 with the ordinary spark-timing levers on automobiles.

I wish it to be understood that I may adapt my invention for various types of magnetos, and also that I may vary the 75 construction of the various parts to suit the requirements.

I do not wish to limit this invention to all of the particular details herein set forth, as various modifications thereof may be 80 made or utilized without departing from the scope of the appended claims.

What I claim as my invention is:

1. In a spark-timing device of the character set forth, a driving shaft, a spirally-formed armature shaft, a connecting member for the two shafts operable longitudinally along the driving shaft and spirally along the armature shaft whereby a longitudinal movement of the said connecting 85 member turns the armature shaft relatively to the driving shaft, a sleeve member for operating the said connecting member longitudinally, a ball-bearing connection between the said sleeve member and the said connecting member whereby the latter may be operated longitudinally while revolving, a housing for the apparatus, the said housing carrying a longitudinally-disposed key 90 working in a longitudinally-formed slot in 100 the said sleeve member whereby the latter is limited to a longitudinal movement only in the said housing, a transversely-disposed ring encircling the said housing and turnable thereon between transversely-disposed flanges on the said housing whereby the said ring is limited to a transverse movement only, the said ring having diagonally-set lugs thereon working in diagonally-formed slots in the said sleeve member whereby 105 turning the said ring on the said housing operates the said sleeve member longitudinally within the said housing, and a friction clutch acting between the said shafts to cause them to revolve evenly together but 110 permitting of a relative turning of the said shafts when the spark-timing mechanism is operated.

2. In a spark-timing device of the character set forth, a driving shaft, a spirally-formed armature shaft, a connecting member for the two shafts operable longitudinally along the driving shaft and spirally along the armature shaft whereby a longitudinal movement of the said connecting 120 member turns the armature shaft relatively to the driving shaft, a sleeve member for operating the said connecting member longitudinally, a ball-bearing connection between the said sleeve member and the said 125

1 connecting member whereby the latter may be operated longitudinally while revolving, a housing for the apparatus, the said housing carrying a longitudinally-disposed key 5 working in a longitudinally-formed slot in the said sleeve member whereby the latter is limited to a longitudinal movement only in the said housing, and a transversely-disposed ring encircling the said housing and 10 in the said housing, and a transversely-disposed flanges on the said housing whereby the said ring is limited to a transverse movement only, the said ring having diagonally-set lugs thereon working in diagonally-formed slots in the said sleeve member 15 whereby turning the said ring on the said housing operates the said sleeve member longitudinally within the said housing.

3. In a spark-timing device of the character set forth, a driving shaft and a driven shaft, one of which is spirally formed, a connecting member for the two shafts operable longitudinally along one and spirally along the other to produce a relative turning 20 thereof, a sleeve member to which the said connecting member is revolubly connected, a housing for the apparatus within which the said sleeve member is keyed so as to be limited to a longitudinal movement 25 only, a transversely-disposed ring encircling the said housing and turnable thereon between transversely-disposed flanges whereby it is limited to a transverse movement only, the said ring having diagonally-set lugs 30 thereon working in diagonally-formed slots in the said sleeve member to operate the latter longitudinally when the said ring is turned and thereby give the said connecting member a longitudinal movement, and a friction clutch 35 acting between the said shafts to cause them to revolve evenly together but permitting of a relative turning thereof when the spark-timing mechanism is operated.

4. In a spark-timing device of the character set forth, a driving shaft and a driven shaft, one of which is spirally formed, a connecting member for the two shafts operable longitudinally along one and spirally 40 along the other to produce a relative turning thereof, a sleeve member to which the said connecting member is revolubly connected, a housing for the apparatus within which the said sleeve member is keyed so as to be limited to a longitudinal movement 45 only, and a transversely-disposed ring encircling the said housing and turnable thereon between transversely-disposed flanges whereby it is limited to a transverse movement 50 only, the said ring having diagonally-set lugs thereon working in diagonally-formed slots in the said sleeve member to operate the latter longitudinally when the said ring is turned and thereby give the said connecting member a longitudinal movement.

5. In apparatus of the character set forth, a driving shaft and a driven shaft, one of which is spirally formed, connecting means for the two shafts operable longitudinally along one and spirally along the other to 70 produce a relative turning thereof, a sleeve member to which the said connecting means is revolubly connected for longitudinal movement, a housing for the apparatus within which the said sleeve member is movable longitudinally, a transversely-disposed ring carried by the said housing and turnable relatively thereto, the said ring having diagonally-set lugs thereon working in diagonally-formed slots in the said sleeve member 75 to operate same longitudinally when the said ring is turned, and a friction clutch acting between the said shafts to cause them to revolve evenly together.

6. In apparatus of the character set forth, 80 a driving shaft and a driven shaft, one of which is spirally formed, connecting means for the two shafts operable longitudinally along one and spirally along the other to produce a relative turning thereof, a sleeve member to which the said connecting means is revolubly connected for longitudinal movement, a housing for the apparatus within which the said sleeve member is movable longitudinally only, and a transversely-disposed ring carried on the outside of the said housing and turnable transversely thereon only, the said ring having diagonally-set lugs 85 thereon working in diagonally-formed slots in the said sleeve member to operate same longitudinally when the said ring is turned.

7. In apparatus of the character set forth, a driving shaft and a driven shaft, one of which is spirally formed, connecting means for the two shafts operable longitudinally along one and spirally along the other to produce a relative turning thereof, a sleeve member to which the said connecting means is revolubly connected for longitudinal movement, a housing for the apparatus within which the said sleeve member is movable longitudinally only, a transversely-disposed ring carried by the said housing and turnable transversely thereon only, the said ring having diagonally-set lugs thereon working in diagonally-formed slots in the said sleeve member 90 to operate same longitudinally when the said ring is turned, and a friction clutch acting between the said shafts to cause them to revolve evenly together.

8. In apparatus of the character set forth, a driving shaft and a driven shaft, one of which is spirally formed, connecting means for the two shafts operable longitudinally along one and spirally along the other to 105 produce a relative turning thereof, a sleeve member to which the said connecting means is revolubly connected for longitudinal movement, a housing for the apparatus within which the said sleeve member is movable 110 longitudinally only, a transversely-disposed ring carried on the outside of the said housing and turnable transversely thereon only, the said ring having diagonally-set lugs thereon working in diagonally-formed slots in the said sleeve member to operate same longitudinally 115 when the said ring is turned, and a friction clutch acting between the said shafts to cause them to revolve evenly together.

9. In apparatus of the character set forth, a driving shaft and a driven shaft, one of which is spirally formed, connecting means for the two shafts operable longitudinally along one and spirally along the other to 120 produce a relative turning thereof, a sleeve member to which the said connecting means is revolubly connected for longitudinal movement, a housing for the apparatus within which the said sleeve member is movable 125 longitudinally only, a transversely-disposed ring carried by the said housing and turnable transversely thereon only, the said ring having diagonally-set lugs thereon working in diagonally-formed slots in the said sleeve member to operate same longitudinally when the said ring is turned, and a friction clutch acting between the said shafts to cause them to revolve evenly together.

longitudinally only, and a transversely-disposed ring carried by the said housing and turnable transversely thereon only, the said ring having diagonally-set lugs thereon 5 working in diagonally-formed slots in the said sleeve member to operate same longitudinally when the said ring is turned.

9. In apparatus of the character set forth, two revolute mechanisms, connecting means 10 for the said mechanisms for causing a relative turning thereof, means for operating the said connecting means comprising a housing, a sleeve operable longitudinally only in the housing, and a ring operable 15 transversely only on the housing, the said ring and sleeve having operable connection with each other, and a friction clutch acting between the said revolute mechanisms to cause them to revolve evenly together.

10. In apparatus of the character set forth, two revolute mechanisms, connecting means for the said mechanisms for causing a relative turning thereof, and means for operating the said connecting means comprising a housing, a sleeve operable longitudinally only in the housing, and a ring operable transversely only on the housing, the said ring and sleeve having operable connection with each other.

11. In apparatus of the character set forth, two revolute mechanisms, connecting means for the said mechanisms for causing a relative turning thereof, means for operating the said connecting means comprising a housing, a sleeve operable longitudinally in the housing, and a ring operable transversely on the housing, the said ring and sleeve having operable connection with each other, and a friction clutch acting between 25 the said revolute mechanisms to cause them to revolve evenly together.

12. In apparatus of the character set forth, two revolute mechanisms, connecting means for the said mechanisms for causing a relative turning thereof, and means for operating the said connecting means comprising a housing, a sleeve operable longitudinally only in the housing, and a ring operable transversely only on the housing, the 45 said ring and sleeve having operable connection with each other.

13. In apparatus of the character set forth having two revolute mechanisms and means for causing a relative turning thereof, operating means for the apparatus comprising a sleeve having longitudinal movement only, and a ring having a transverse movement only, the said ring and sleeve having operable connection with each other.

14. In apparatus of the character set forth having two revolute mechanisms and means for causing a relative turning thereof, operating means for the apparatus comprising a member having longitudinal movement only, and another member having a trans-

verse movement only, the said members having operable connection with each other.

15. In apparatus of the character set forth, operating mechanism therefor comprising a member having longitudinal movement 70 only, and another member having a transverse movement only, the said members being operably connected so that the operation of one causes the operation of the other.

16. In a spark-timing device for ignition 75 magnetos, a driving shaft, an armature having a shaft connected therewith a portion of which shaft is spirally formed, a collar member having finger portions thereon adapted to slide longitudinally in longitudinal slots in the driving shaft member and having a spirally-formed hole therethrough fitting the said spirally-formed portion of the armature shaft and slidably along said spirally-formed portion whereby a longitudinal movement of the said collar portion shifts the armature shaft forwardly or backwardly relatively to the driving shaft, a sleeve member, a ball bearing attached to the said collar member and to the said sleeve member whereby the said collar member may be rotated relatively to the said sleeve member and whereby the said collar member and the said sleeve member are movable longitudinally along the driving shaft together 85

<p

shaft and slidably therealong whereby a longitudinal movement of the said collar portion turns the armature shaft relatively to the driving shaft, a sleeve member, a ball bearing attached to the said collar member and to the said sleeve member whereby the said collar member may be rotated relatively to the said sleeve member and whereby the said collar member and the said sleeve member are movable longitudinally along the said shafts together, a housing for the said sleeve member, means for moving the said sleeve member along the said shafts within the said housing, and a crab-like friction clutch acting between the armature shaft and the driving shaft to cause the armature shaft to turn smoothly with the driving shaft but permitting the armature shaft to turn relatively to the driving shaft when the spark-timing mechanism is operated.

18. In a spark-timing device for magnetos, a driving shaft, a spirally-formed armature shaft, a connecting member for the two shafts operable longitudinally along the driving shaft and spirally along the armature shaft whereby a longitudinal movement of the said connecting member turns the armature shaft relatively to the driving shaft, a sleeve member, a ball bearing connected between the said connecting member and the said sleeve member whereby these members are operable along the said shafts together and whereby the said connecting member may be rotated relatively to the said sleeve member, means for moving the said sleeve member along the said shafts, and a friction clutch, acting between the said shafts with sufficient force to eliminate the usual intermittent jerk on the armature due to the intermittent uneven magnetic pull thereon and thereby cause the armature to turn smoothly with the driving shaft, but permitting the armature shaft to turn relatively to the driving shaft when the spark-timing mechanism is operated.

19. In a spark-timing device of the character set forth, a driving shaft, a spirally-formed armature shaft, a connecting member for the two shafts operable longitudinally along the driving shaft and spirally along the armature shaft whereby a longitudinal movement thereof causes a relative turning of the two shafts, means for operating the said connecting member along the said shafts comprising a ball bearing connection with the said connecting member whereby the latter may be operated along the said shafts while revolving, and a friction clutch acting between the two shafts with sufficient force to eliminate the usual intermittent jerk on the armature due to the intermittent uneven magnetic pull thereon and thereby cause the armature to turn smoothly with the driving shaft, but permitting the armature shaft to

turn relatively to the driving shaft when the spark-timing mechanism is operated.

20. In a spark-timing device of the character set forth, a driving shaft and a driven shaft, connecting means for the shafts, means for operating the said connecting means along the shafts to produce a relative turning of the latter, said operating means having a ball-bearing connection with the said connecting means whereby the latter may be operated longitudinally while revolving, and a friction clutch acting between the said shafts with sufficient force to eliminate the usual intermittent jerk on the driven shaft due to the intermittent uneven magnetic pull thereon and thereby cause the driven shaft to turn smoothly with the driving shaft, but permitting the driven shaft to turn relatively to the driving shaft when the spark-timing mechanism is operated.

21. In apparatus of the character set forth, two revoluble mechanisms, means for coupling the said mechanisms to cause them to rotate together, means for operating the said coupling means to produce a relative turning of the said mechanisms, the said operating means being connected with the said coupling means by a ball bearing whereby the said coupling means may revolve while being operated by the said operating means, and a friction clutch acting between the said revoluble mechanisms with sufficient force to eliminate any ordinary jerking movement therebetween and thereby cause them to revolve smoothly together, but permitting one of the said revoluble mechanisms to turn relatively to the other upon the application of a greater force.

22. In a spark-timing device for magnetos, a driving shaft, an armature shaft a portion of which is spirally formed, a collar member having finger portions thereon adapted to slide longitudinally in longitudinal slots in the driving shaft member and having a spirally-formed hole therethrough fitting the said spirally-formed portion of the armature shaft and slidably therealong whereby a longitudinal movement of the said collar portion turns the armature shaft relatively to the driving shaft, a ball-bearing connection with the said collar member whereby it may be rotated and at the same time moved along the said shafts, and a friction clutch acting between the said shafts with sufficient force to eliminate the usual intermittent jerk on the armature shaft due to the intermittent uneven magnetic pull thereon and thereby cause the armature shaft to turn smoothly with the driving shaft but permitting the armature shaft to turn relatively to the driving shaft when the spark-timing mechanism is operated.

23. In a spark-timing device of the

- character set forth, a driving shaft and a spirally-formed driven shaft, connecting mechanism for the two shafts, means for operating the said connecting mechanism longitudinally along one of the shafts and spirally along the other for producing a relative turning of the shafts, the said means comprising a ball-bearing connection with the said connecting mechanism whereby the latter may be operated along the said shafts while revolving, and a friction clutch acting between the two shafts with sufficient force to eliminate the usual intermittent jerk on the driven shaft due to the intermittent uneven magnetic pull thereon and thereby cause the driven shaft to turn smoothly with the driving shaft, but permitting the driven shaft to turn relatively to the driving shaft when the spark-timing mechanism is operated.
24. In a spark-timing device for magnetos, a driving shaft, a spirally-formed armature shaft, a connecting member for the two shafts operable longitudinally along the driving shaft and spirally along the armature shaft whereby a longitudinal movement of the said connecting member turns the armature shaft relatively to the driving shaft, a ball-bearing connection with the said connecting member whereby it may be rotated and at the same time moved along the said shafts, and a friction clutch acting between the said shafts with sufficient force to eliminate the usual intermittent jerk on the armature shaft due to the intermittent uneven magnetic pull thereon and thereby cause the armature shaft to turn smoothly with the driving shaft, but permitting the armature shaft to turn relatively to the driving shaft when the spark-timing mechanism is operated.
25. In a spark-timing device of the character set forth, a driving shaft, a spirally-formed armature shaft, a connecting member for the two shafts operable longitudinally along the driving shaft and spirally along the armature shaft whereby a longitudinal movement thereof causes a relative turning of the two shafts, means for operating the said connecting member along the said shafts, and a friction clutch acting between the said shafts with sufficient force to eliminate the usual intermittent jerk on the armature shaft due to the intermittent uneven magnetic pull thereon and thereby cause the armature shaft to turn smoothly with the driving shaft, but permitting the armature shaft to turn relatively to the driving shaft when the spark-timing mechanism is operated.
26. In a spark-timing device of the character set forth, a driving shaft and a spirally-formed driven shaft, connecting mechanism for the two shafts, means for operating the said connecting mechanism longitudinally along one of the shafts and spirally along the other for producing a relative turning of the shafts, and a friction clutch acting between the two shafts with sufficient force to eliminate any ordinary jerking movement therebetween and thereby cause them to turn smoothly together, but permitting the driven shaft to turn relatively to the driving shaft when the spark-timing mechanism is operated.
27. In a spark-timing device of the character set forth, a driving shaft and a driven shaft, connecting means for the shafts, means for operating the said connecting means along the shafts to produce a relative turning of the latter, and a friction clutch acting between the two shafts with sufficient force to eliminate any ordinary jerking movement therebetween and thereby cause them to turn smoothly together, but permitting the driven shaft to turn relatively to the driving shaft when the spark-timing mechanism is operated.
28. In apparatus of the character set forth, two revoluble mechanisms, means for coupling the said mechanisms to cause them to rotate together, means for operating the said coupling means to produce a relative turning of the said mechanisms, and a friction clutch acting between the said mechanisms with sufficient force to eliminate any ordinary jerking movement therebetween and thereby cause them to revolve smoothly together, but permitting one of the said revoluble mechanisms to turn relatively to the other upon the application of a greater force.
29. In a spark-timing device comprising two revoluble mechanisms, connecting means therefor for producing a relative turning of the said mechanisms, means for operating the said connecting means to produce the said relative turning, and a friction clutch acting between the said mechanisms with sufficient force to eliminate any ordinary jerking movement therebetween and thereby cause them to revolve smoothly together, but permitting one of the said revoluble mechanisms to turn relatively to the other upon the application of a greater force.
30. In a spark-timing mechanism having a driving member and a driven member, and means for causing an angular displacement of one of the said members relatively to the other, a friction clutch acting between the said members with sufficient force to eliminate any ordinary jerking movement therebetween and thereby cause them to turn smoothly together, but permitting the driven member to turn relatively to the driving member when the spark-timing mechanism is operated.
31. In apparatus of the character set

forth; a driving shaft, a driven shaft, an adjustable connection between the said shafts for causing a relative angular displacement thereof, and a crab-like friction clutch attached rigidly to one of the said shafts and having curved spring arms sprung out against the inner surface of a cup-shaped portion on the other said shaft, to cause the said shafts to turn evenly together.

32. In apparatus of the character set forth having two revoluble mechanisms and means for causing a relative angular displacement thereof, a friction clutch acting between the said mechanisms with sufficient force to eliminate any ordinary jerking movement therebetween and thereby cause them to revolve smoothly together, but permitting one of the said revoluble mechanisms to be angu-

larly displaced relatively to the other upon the application of a greater force.

33. In apparatus of the character set forth having two revoluble mechanisms and means for causing a relative turning thereof, means for causing the said mechanisms to revolve smoothly together so as to eliminate any ordinary relative movement therebetween due to undesirable forces, but permitting a relative turning therebetween upon the application of a greater predetermined force.

As inventor of the foregoing I hereunto subscribe my name, this 28th day of February, 1912.

WILHELM CARL BERLING.
